Letters Patent No. 1042. Dated, Aug. 17, 1858.

The schedule referred to in these Letters Patent and making part of the same.

To all whom it may concern:

Be it known, That we, Jacob Steffe, James Horton and John Currie, of the City of Philadelphia, in the County of Philadelphia and State of Pennsylvania, have invented or produced a new and original design for a stove termed the "Fancy Egg," and we do hereby declare the following to be a full, and exact description of the same, reference being had to the accompanying drawing, which forms a part of this specification, and which represents parts of the said Stove in perspective.

The Stove consists of four plates A. B. C. and D. The plate A. forms the base and ash pit, that portion on which the plate B. rests being edged with a molding ornamented with sprigs, &c. the portion which forms the ash pit having foliated and other ornaments. The plate B. which intervenes between the body of the Stove and the base, forms a molding ornamented with leaves and edged with a denticulated beading. The body C. of the Stove is surrounded about midway between its two ends with an ornamented belt a. above and below which are series of projecting beads. The upper edge of the body C. is plain, for the reception of a sheet iron cylinder on the top of which rests the cap D. In the center of the latter is an ornamental boss, surrounded with two ornamental moldings, the whole being edged with an open scroll molding. We claim

The combination and arrangement of ornamental figures and forms, represented in and by the accompanying drawing, and forming together an ornamental design for a Stove.
